THRUST PLATES FOR ROTARY PUMPS AND MOTORS

Thomas C. Kane, deceased, late of Youngstown, Ohio, by
Dollar Savings and Trust Company, executor, Youngs-
town, Ohio, assignor to The Commercial Shearing and
Stamping Company, a corporation of Ohio

Filed Nov. 29, 1957, Ser. No. 699,801

7 Claims. (Cl. 103—126)

The present invention relates to a thrust plate for a rotary pump or motor and particularly to a thrust plate adapted for use in gear pumps and motors operating at relatively high pressures.

Conventional gear pumps and motors are well-known. They have operated in the past at pressures generally below 1500 p.s.i. because of difficulties in maintaining their end plates against the rotary pumping gears and because of the erosion of the end plates at high pressures. Recent developments in rotary pump and motor design have made it possible to maintain the end plates in position at pressures in the neighborhood of 3000 p.s.i. but have only accentuated the erosion problem. Rotary pumps and motors operating at these higher pressures have been consistently plagued with the problem of erosion of the thrust plates adjacent the meshing point of the gears. As the gears mesh, a certain amount of oil is squeezed out of its trapped position between the gear teeth axially of the gears. This fluid strikes the thrust plate at very high pressures and considerable difficulty has been experienced at the meshing point by reason of the erosion caused by this high pressure sideways jetted oil.

The present invention overcomes this difficulty and provides a structure which substantially eliminates the erosion at the meshing point of the gears. According to this invention, a thrust plate will have four to five times the working life of a conventional thrust plate without any detriment to the pumping action or the freedom of movement of the rotary gears.

This invention provides a thrust plate comprising a metal body in the general form of a figure 8, the body having a front face adapted to abut the gear or impeller ends, a pair of openings through the plate on opposite sides of the waist of the figure 8 adapted to receive the impeller shafts or hubs, and a thin insert of abrasion-resistant alloy inlaid at the waist of the figure 8 along the meshing point of the gear teeth. Hereafter in this application when impeller shafts are mentioned, it shall for simplicity, include both impeller shafts or hubs as the case may be. Preferably, the inlaid piece of abrasion-resistant material is a thin circle of hard bronze sold under the name "Ampco" or similar abrasion resisting alloy and the main body of the plate is made of a leaded bronze. The leaded bronze carries the high bearing loads that occur between the thrust plate and the gears and the "Ampco" disk which is inlaid in the surface of the leaded bronze takes the abrasive action of the jetting oil extruded from between the gear teeth, thus preventing erosion of the thrust plate.

While there have been set out hereinabove certain purposes, advantages and objects of the present invention, other objects, advantages and purposes will be apparent from the following description and the accompanying drawings in which,

Figure 1 is a partial section through a gear pump showing the thrust plate in position;

2

Figure 2 is a plan view of the thrust plate according to the present invention; and

Figure 3 is a section on the line III—III of Figure 2.

Referring to the drawings, there is illustrated a rotary pump housing 10, having a pair of meshing gear impellers 11 and 12 between a pair of end plates 13 and 14 with a central casing member 15 enclosing the outer peripheries of the impellers and plates. The plates 13 and 14 and casing member 15 are enclosed between a pair of 10 end casing members 16 and 17 and held together by bolts 18 extending through the casing members to hold said members together in tightly sealed relation. The invention will be particularly described with respect to one of the thrust plates 14. The plate 14 is in the form 15 of a figure 8 having a pair of openings 24 and 25 throughout which hubs 22 and 23 extend. These openings are countersunk on the rear face of the plate to provide counterbores 26 and 27 fitting closely around bearing shells 19 and 20. The front face of the plate 20 14 is provided with flat surfaces fitting closely against the adjacent impeller ends and with two pairs of grooves 28 which serve to carry fluid pressed between the meshing impeller teeth back to the low pressure side of the pump regardless of the direction of rotation of the impellers. 25 A circular insert 29 of "Ampco" is inlaid into a shallow well 30 in the waist 31 of the thrust plate 14 so as to lie on an axial line through the meshing point of the gear teeth. Oil ejected sideways from the meshing gear teeth of the impellers 11 and 12 is jetted against the 30 insert 29 and any which leaks by this plate is carried toward the grooves 28. Rubber-like seals 33 are provided in channels 34 in the rear face of the plate. Each such rubber-like seal rises above the top of the channel in which it is placed. These seals act to form differential pressure areas on the rear face of the plate which maintain the plate in desired contact with the ends of the impeller.

The plate 13 corresponds identically with the plate 40 14 in construction, mounting and operation. As in the case of plate 14, the "Ampco" insert 29 lies on the axis of the meshing plate between the rotary impellers 11 and 12.

The "Ampco" insert 29 is preferably applied by pressing into the well 30 although any suitable method of 45 affixing the insert in the end plates 13 and 14 may be used. For example, the insert may be cemented in place by a plastic resin cement or it may be cast into the plate, or it may be physically fixed in the plate by peening the bronze bearing metal over the "Ampco" disk. Other 50 abrasion-resisting materials may be used in place of "Ampco" for the disk 29. For example, cemented carbide disks or other like abrasion-resistant materials may be used. As in the case of "Ampco," these disks may be applied in any satisfactory method. The insert need 55 not be circular in shape but may take any convenient, desired form so long as it covers the area in which the gear teeth mesh and may eject oil to erode the plate. The thrust plate of the present invention provides the necessary high bearing load capacity along with resistance 60 to the abrasive jetting action of the high pressure oil at the several points where these two characteristics are necessary.

While certain preferred forms and practices of this invention have been set out hereinabove, it will be understood that the invention may be otherwise embodied within the scope of the following claims.

What is claimed is:

1. In a rotary gear pump having a case, a pair of 70 rotary gears in said case, the improvement comprising a unitary thrust plate for the corresponding ends of the pair of cooperating rotary gears adapted to lie between

the case and the gears comprising a soft metal body having a front face adapted to abut the impeller ends, a pair of openings extending through the body to receive the impeller shafts and an inlay of abrasion-resistant material spaced from and intermediate between said openings on the line formed between the meshing gear teeth at the intermesh point of the rotary gears and receiving the fluid forced axially from the gear teeth.

2. In a rotary gear pump having a case, a pair of rotary gears in said case, the improvement comprising a 10 unitary thrust plate for the corresponding ends of the pair of cooperating rotary gears adapted to lie between the case and the gear comprising a leaded bronze body in the form of a figure 8, said body having a front face adapted to abut the impeller ends, a pair of openings extending through the body to receive the impeller shafts and an inlay of abrasion-resistant material flush with said face, spaced from and between said openings and on the axial line formed between the meshing gear teeth at the intermesh point of the rotary gears, said inlay receiving the fluid forced axially from the gear teeth.

3. In a rotary gear pump having a case, and a pair of rotary gears thereon, a thrust plate as claimed in claim 2 wherein the inlay is a disc of hard bronze.

4. In a rotary gear pump having a case, and a pair of rotary gears thereon, a thrust plate as claimed in claim 3 wherein the disc is silver soldered into a well in the plate.

5. In a rotary gear pump having a case, and a pair of rotary gears thereon, a thrust plate as claimed in claim 3 wherein the inlay disc is pressed into a shallow well in the plate in frictional engagement therewith.

6. In a rotary gear pump having a case, and a pair of rotary gears thereon, a thrust plate as claimed in claim 3 wherein the inlay disc is cemented into a shallow well in the plate.

7. In a rotary gear pump having a case, and a pair of rotary gears thereon, a thrust plate as claimed in claim 3 wherein the plate is cast about the inlay disc.
